DRESSING APPARATUS FOR GRINDING WHEELS
Stanley William Hoare, Peterborough, England, assignor
to Newall Engineering Company Limited, Peterborough,
England, a British company

Filed Nov. 18, 1964, Ser. No. 412,210

4 Claims. (Cl. 125—11)

This invention relates to apparatus for dressing grinding wheels which have cylindrical grinding surfaces.

According to this invention in one aspect there is provided a method of dressing a grinding wheel employing a dressing device which has a first dressing portion for dressing a cylindrical surface of the wheel and a second dressing portion for dressing a surface of the wheel which faces in an axial direction or in a direction having an axial component, in which method the point or points of contact between the first dressing portion and the cylindrical surface of the wheel move in a direction parallel to the axis of the grinding wheel, and the second dressing portion is brought into dressing engagement with the other said surface of the wheel.

According to this invention in another aspect there is provided dressing apparatus comprising a support structure, and a device for dressing a grinding wheel, which device is mounted in the support structure and has a first dressing portion for dressing a cylindrical surface of the wheel, and a second dressing portion for dressing a surface of the wheel which faces in an axial direction or a direction which has an axial component, the point or points of contact between the first dressing portion and the cylindrical surface of the wheel being movable laterally for traversing the cylindrical surface of the wheel.

The first dressing portion may comprise a single point dressing element, and in this case means is provided for moving the dressing element laterally for traversing the cylindrical surface of the grinding wheel.

In alternative arrangements said dressing portions are annular and coaxial with each other, and the apparatus comprises means for rotating the dressing portions and means for moving at least the first dressing portion parallel to the axis of rotation of the dressing portions for traversing the cylindrical surface of the grinding wheel. The first dressing portion may be formed with a series of peripheral ribs, the radially outer surfaces of which are adapted for dressing the cylindrical surface of the grinding wheel.

In other preferred arrangements the first dressing portion comprises a member formed with an external helical rib, the radially outer surface of which rib is adapted for dressing the cylindrical surface of the grinding wheel, the second dressing portion is annular and coaxial with the rib, and the apparatus comprises means for rotating said dressing portions about their common axis. In this construction means may be provided for moving at least the first dressing portion parallel to said common axis for traversing the cylindrical surface of the grinding wheel.

The dressing device may comprise a third dressing portion for dressing a third surface of the grinding wheel which surface faces in an axial direction or a direction having an axial component, the second and third portions being disposed one on each side of the first dressing portion.

Preferably said dressing portions are all traversed together by the traversing means.

The first dressing portion may be spaced from the second and, where provided, the third dressing portions by a distance piece or distance pieces, the dressing portions and distance piece or pieces being detachably secured together as a unit for mounting in the apparatus.

2

Some embodiments of the invention will now be described by way of example. The description makes reference to the accompanying drawings in which:

FIGURE 1 shows one form of a dressing wheel according to the invention, and

FIGURE 2 shows a second form of a dressing wheel according to the invention.

For dressing the cylindrical surface 10a of a grinding wheel 10 and the two radiussed corner portions 10b, 10c at the ends of the cylindrical surface, a dressing machine or attachment 5 is provided comprising a dressing wheel 6 mounted on a supporting structure 7, which is in turn mounted on compound slide structure for movement parallel to and perpendicularly to the axis of rotation of grinding wheel 10.

In the construction of dressing wheel shown in FIGURE 1 the wheel comprises a first annular dressing portion 11 for dressing the cylindrical surface 10a of grinding wheel 10, and second and third annular dressing portions 12, 13 shaped for respectively dressing the two corner portions 10b, 10c at opposite ends of the cylindrical surface of the grinding wheel 11. The dressing surfaces of dressing portions 11, 12 and 13 are diamond impregnated.

The dressing portions 11, 12 and 13 are carried on a central spindle 14, which has a head 15 at one end, and are prevented from rotating relative to the spindle by respective keys 16. Two spacing rings 17 serve to space dressing portion 11 from portions 12 and 13 respectively. A washer 18 abuts the dressing portion 13 and the assembly is secured together between the head 15 of spindle 14 and the washer 18 by a nut 19 engaged on a threaded end portion of the spindle. Head 15 is formed with radially extending recesses in which dogs 20 on a driven shaft 21 engage. The spindle is journaled on centres 21a, 22 which engage in corresponding recesses in opposite ends of the spindle 14.

In use, the dressing wheel is disposed with its axis parallel to that of the grinding wheel. The dressing wheel is moved forward at right angles to its axis until it is in the position shown in the drawing relative to the grinding wheel, i.e. with one or other of the dressing portions 10b, 10c in engagement with the corresponding corner portion of the grinding wheel. While the grinding wheel is rotating, the dressing wheel is then traversed parallel to its axis of rotation so that the dressing portion 11 traverses the cylindrical surface 10a of the grinding wheel. The dressing wheel is traversed backwards and forwards with successive cuts and the dressing portions 12 and 13 dress the corner of the grinding wheel at the ends of the traversing movement.

The spacing rings 17 are of such a length that the dressing portion 11 will traverse the full width of the cylindrical surface of the grinding wheel from the position in which the dressing wheel is shown in the drawing before the corner portion 13 comes into contact with the corresponding corner portion of the grinding wheel.

The traversing of the cylindrical surface of the grinding wheel by the dressing portion 11 ensures that the surface 10a of the grinding wheel is truly cylindrical and imparts to the grinding wheel the capacity to produce a good overall finish on the cylindrical surface to be ground.

The spacing rings 17 can be replaced by other rings having different axial lengths to enable grinding wheels of different axial lengths to be treated.

An alternative form of dressing wheel is shown diagrammatically in FIGURE 2 and comprises two end dressing portions 24, 25 corresponding to the portions 12 and 13 in the arrangement shown in FIGURE 1, and a central dressing portion 26 disposed between portions 24, 25. The central portion 26 has a helical rib 27 along its outer

surface which rib extends over the full length of the central portion. The dressing surfaces of the portions 24, 25, and rib are impregnated with diamond dust.

The central portion 26 has a greater axial length than the cylindrical surfaces of the grinding wheel to be dressed, and the dressing wheel is used in the same apparatus and in the same way as that shown in FIGURE 1. Thus the central portion 26 engages the cylindrical surface of the grinding wheel while the latter is rotating about its own axis, and the dressing wheel is rotated and moved to and fro parallel to its own axis to bring the two portions 24, 25 alternately into dressing engagement with the corresponding portions of the grinding wheel. In this arrangement however the dressing wheel 23 need be traversed only a short distance in a direction parallel to its axis of rotation. This arrangement is intended for use where the arrangement shown in FIGURE 1 cannot be used, for example because of possible interference with parts adjacent the grinding wheel. Alternatively, the central portion 26 may have the same axial length as the cylindrical surface of the grinding wheel, the dressing wheel being moved radially, without any axial component, into engagement with the grinding wheel.

In another arrangement, not illustrated, the central portion 26 has a series of spaced annular ribs and in this case the dressing wheel is rotated and traversed to and fro parallel to its own axis as in the arrangement of FIGURE 1.

In yet another arrangement, not illustrated, the rotary dressing portion 11 in FIGURE 1 is replaced by a single-point diamond, and the rotary dressing portions 12 and 13 are replaced by non-rotary cutting portions. In this case the dressing device is presented to the surface of the grinding wheel and is traversed to and fro parallel to the axis of rotation of the grinding wheel between the positions in which the two corner-shaping portions respectively engage the corners of the grinding wheel. As before, the distance between the corner-shaping portions is greater than the distance between the corners of the grinding wheel to a degree such that the diamond can traverse the full width of the peripheral surface of the grinding wheel in the same manner as described in relation to FIGURE 1.

I claim:

1. A dressing apparatus for use with a grinding wheel of cylindrical form having a cylindrical curved surface, flat end surfaces and a rounded end portion between said curved surface and each of said flat end surfaces, comprising a first cylindrical dressing roller for dressing the cylindrical surface of the wheel, a second cylindrical dressing roller having a surface complementary to one of said rounded end portions of said grinding wheel, said second roller being mounted coaxially with respect to said first roller, means for rotating said rollers about an axis parallel to that of said grinding wheel, means for moving said rollers in an axial direction, a sufficient distance to cause said first roller to traverse the full width of the cylindrical surface of said grinding wheel, said first and second grinding rollers being spaced along said common axis such that said second grinding roller contacts the

rounded end portion of said grinding wheel only after said first roller has reached the opposite end thereof.

2. Dressing apparatus as claimed in claim 1 further comprising a third cylindrical dressing roller having a surface complementary to the rounded end portion of said grinding wheel opposite that contacted by said second dressing roller, said third dressing roller being mounted for rotation and axial movement on the side of said first dressing roller opposite that of said second dressing roller, said first and third dressing rollers being spaced along said common axis such that said third dressing roller contacts its respective rounded end portion of said grinding wheel, only after said first roller has reached the other end thereof.

15 3. A method of dressing a grinding wheel of cylindrical form having a cylindrical curved surface and flat end surfaces and a rounded portion between said curved surface and each of said flat end surfaces, comprising the steps of bringing into engagement with 20 said curved surface a first cylindrical dressing roller, the axes of said first dressing roller and said grinding wheel being parallel at the time of engagement; traversing said first cylindrical roller in a first axial direction to dress the full width of the cylindrical surface of 25 said grinding wheel; bringing into engagement, after said traversing in said first axial direction, with one of said rounded portions and said flat surfaces of said grinding wheel, a second dressing roller, said second dressing roller having a surface complementary to said rounded portion 30 and said flat surface, said second roller being mounted coaxially with and spaced apart from said first roller.

35 4. A method as set forth in claim 3 further comprising after said traversing in said first axial direction, traversing said first cylindrical roller in a second axial direction 40 opposite to said first axial direction to dress the full width of the cylindrical surface of said grinding wheel, and then bringing into engagement with the other of said rounded portions and said flat surfaces of said grinding wheel a third dressing roller, said third dressing roller having a surface complementary to said other rounded portion and said other flat surface and said third roller being mounted co-axially with and spaced apart from said first and second dressing rollers.
